TOOL MOUNTING

Michael D. Dzama, Cleveland, Ohio

Application March 6, 1943, Serial No. 478,218

11 Claims. (Cl. 279—6)

This invention relates to a tool mounting whereby the tool may be readily and accurately adjusted from time to time relative to its support for carrying out boring or other operations. As showing one application of my improvement in mounting, it is illustrated as adjustably supporting the tool of a boring mill, whereby the tool may be adjusted radially into operating position.

One object of the invention is to provide an improved mounting of this character capable of fixedly maintaining the shank of the tool in its adjusted position.

Another object of the invention is to provide an improved tool mounting of this character wherein the adjustment of the part or element which supports the tool shank, may be moved predetermined distances without danger of backlash, whereby setting of the tool with respect to the work is facilitated.

Another object of the invention is to provide an improved mounting of this character comprising few parts capable of ready assembly and inter-related to simplify and economize their construction.

Another object of the invention is to provide an improved mounting of this character all the parts of which may be completely assembled before installation in the support or casing on the mill.

Another object of the invention is to provide an improved mounting of this character having a movable supporting member for the tool shank and guide walls therefor, certain of the guide walls being adapted to be flexed to increase the friction between it and the supporting member.

Other objects of the invention will be apparent to those skilled in the art to which my invention relates from the following description taken in connection with the accompanying drawing, wherein:

Fig. 1 is a side elevation of a mounting embodying my invention, with a tool supported therein and showing the operation of the latter for carrying out a boring operation.

Fig. 1a is a section on the line 1a—1a of Fig. 1.

Fig. 2 is a section on the line 2—2 of Fig. 3.

Fig. 3 is a section on the line 3—3 of Fig. 2.

Figs. 4 and 5 are sections on the lines 4—4 and 5—5, respectively, of Fig. 2.

Fig. 6 is a fragmentary elevation on the line 6—6 of Fig. 4.

In the drawing, 1 indicates the tail stock of a boring mill arranged to receive the shank 2 of a hollow casing 3, in which a mounting, indi-

cated as an entirety at 4, is removably mounted, the end of the casing remote from the shank 2 being open to receive the mounting 4. The mounting 4 consists of the following elements: 5 indicates as an entirety a guide member for a movable or adjustable member 6, in which the shank A of the tool B is removably supported as later set forth. The guide member 5 comprises a base 5' having at its opposite ends upstanding walls 5a, 5a', the surface 5x of the base between the walls 5a, 5a', forming a slide wall or way for the supporting member 6 and each of the walls 5a, 5a', serving to limit the adjustment of the member 6 when moved in one direction.

10 The outer wall 5x' of the base 5' is of curvilinear shape to fit the inner wall of the casing 3, and intermediate the slide wall 5x and bottom wall of the base 5', the latter is formed with a slot 7 (preferably extending therethrough at right angles to the axis of the casing), the upper wall of which is preferably normally parallel to the slide wall 5x. 8, 9, indicate spaced guide devices supported at their opposite ends in recesses formed in the upstanding walls 5a, 5a' and rigidly secured thereto by countersunk screws 10. The opposite ends of the guide devices 8, 9, are rounded off so as to fit the inner wall of the casing 3.

15 By preference, the wall of one guide device—the outer device 9 for example—is extended and curvilinearly shaped from end to end to fit the inner wall of the casing 3. The side walls of the guide devices 8, 9, are preferably inclined downwardly and inwardly and fit correspondingly shaped recesses 6a formed in the upper wall of the member 6 to guide the latter.

20 From the foregoing description it will be observed that the member 6 slides on the way 5x and is guided by the devices, 8, 9, in a direction at right angles to the axis of the casing 3. Suitable countersunk screws 11 disposed radially of the casing 3 and extended into and through openings 12 formed in the side wall of the casing 3 and threaded into openings formed in the base 5', serve to secure the mounting in the casing 3.

25 The outer end of the supporting member 6 is formed with an inwardly extending opening 6b, and provided with a boss 6b' therearound, the opening forming a seat for the inner end of the tool shank A, which is secured therein by a set screw 13 threaded through the boss 6b' and a set screw 14 threaded into an opening 6c formed in the member 6.

30 As shown in Fig. 5, the insertion of and access

to the screw 14 is provided for by aligned openings 14a', 14a, formed in the wall 5a and casing 3, respectively.

The supporting member 6 inwardly of the shank seat 6b is formed with a through opening 15 extending at right angles to and having an axis intersecting the axis of the casing 3. The wall of the opening 15 from end to end thereof is provided with screw threads of any desired pitch and accommodates and supports a feed screw 16, the opposite ends of which abut the inner faces of the upstanding walls 5a, 5a', whereby endwise movement of the screw 16 is prevented.

As will be observed in Figs. 3, 4 and 5, the width of the member 6 is less than the distance between the walls 5a, 5a', so that by turning the screw 16 the supporting member 6 may be moved on the way 5x into engagement with either wall. At one end the feed screw 16 is provided with an axially disposed hollow extension 17, the inner wall of the extension being shaped in cross section to receive a key, whereby the screw may be rotated, whereas its outer end portion is exteriorly threaded, whereby a suitable dial 18 may be secured to the extension 17, and by means of suitable graduations and indicia thereon, determine the angular movement of the screw and the measured adjustment of the member 6, to position the tool B for boring, as shown in Figs. 1 and 1a. The casing 3 is formed with an opening 19 to accommodate the dial 18. By preference, the outer annual face of the dial 18 does not extend beyond the outer wall of the casing 3 and conforms to the curvature thereof to eliminate any protruding portion thereof.

20 indicates a through opening formed in the base 5' between its bottom wall and the slot 7, in a plane at right angles to the slot and midway between the planes of the walls 5a, 5a'. The wall of the opening 20 is provided with screw threads to take a screw 21 which is tightened against the top wall of the slot 7, the effect of which is to flex the wall of the base 5', (the metal of the base 5' being of a character to permit such operation) between the walls 5a, 5a', upwardly approximately one-ten thousandths of an inch, so that the intermediate portion of the slide way 5x is forced against the supporting member 6 to insure friction between these parts and thus prevent free movement of the member 6. Accordingly, resistance to turning of the dial is provided to prevent it being easily turned, except by a definite applied force, so that when operated, danger of the dial being turned beyond the desired angular distance is substantially eliminated. The casing 3 is formed with an opening 22, in registry with the opening 20, to permit access to the screw 21.

It will be observed that all of the parts constituting the mounting may be assembled with the guides in rigid relation and inserted as a unit into the casing 3. By preference, the outer walls of the guides 5, 8 and 9 have a close sliding, substantially pressed-in fit with the inner walls of the casing 3, so that the screws 11 merely serve to prevent relative movement between these parts. The outer end of the casing may be provided with a removable cover (not shown). To permit the screw 16 and supporting member 6 to be assembled in the guide member 5, the upstanding wall 5a is formed with an inwardly extending elongated recess or slot 5a''.

23 indicates a transverse opening or slot formed in and extending longitudinally of the guide de-

vice 9 and 24 indicates a through opening formed in the guide device intermediate its ends and extending from the opening 23 outwardly radially of the casing 3. The walls of the opening 24 are provided with screw threads to take a screw 25 which may be tightened against the lower wall of the opening 23 to slightly flex it and thereby increase the friction between the side walls of the guide device 9 and guide surfaces 6a of the supporting member 6, to thereby supplement the friction between guide way 5x and the member 6. However, due to the fact that the wall of the guide device engaged by the screw is connected to the walls of the device 9 at its ends only, it may be flexed sufficiently by the screw 25 to bind its guide surfaces to the guide surfaces 6a of member 6, so that when the latter is adjusted the screw 25 may be further tightened and serve as the means for locking the member 6 against movement. The casing 3 is formed with an opening 26 to permit access to the screw 25.

It will also be observed that the mounting consists of few parts employing a main guide member, for one side of the slideable member 6 and separate guide members for the opposite side thereof, which members have outer walls complementary to and engaging diametrically opposite inner walls of the casing 3.

As shown in Figs. 3 and 5, when the supporting member 6 is positioned against the upstanding wall 5a, the axis of the tool shank A is in axial alignment with the axis of the casing 3, so that rotation of the dial 18 to rotate the screw 16 serves to move the member 6 and tool shank 35 A radially of this axis a predetermined distance determined by the angular movement of the dial 18, it being understood that the graduations thereon have a fixed relation to the pitch of the screw threads on the screw 16.

40 It will also be noted that the tool support 6 is movable between fixed guides and that the operating or feed screw is supported substantially from end to end entirely by the support, but held against endwise movement by engagement with walls 5a, 5a' which form part of one of the guides. This arrangement eliminates the employment of bearings for the feed screw at opposite ends thereof and insures at all times alignment of the feed screw with the threaded opening in the support 6 as well as engagement between the screw threads from end to end of the support, so that danger of back-lash in making an adjustment is avoided. It also enables the assembly to be made of a minimum number 55 of parts and reduces the area of the surfaces that have relatively moving contact.

To those skilled in the art to which my invention relates many changes in construction and widely differing embodiments and applications 60 of the invention will suggest themselves without departing from the spirit and scope of the invention. My disclosures and the description herein are purely illustrative and are not intended to be in any sense limiting.

65 What I claim is:

1. In a tool mounting, the combination with a casing adapted to be supported on a machine, of a movable member for supporting the shank of a tool, a set of guides seated in said casing 70 and engaging the opposite sides of said member to slidably support it therebetween and the inner walls of said casing, means for connecting said guides together, said member being formed with a through screw threaded opening, a feed screw supported in said opening, means on one of said

guides abutting the opposite ends of said screw to prevent axial movement thereof, and means for securing one of said guides to said casing.

2. A mounting as claimed in claim 1 wherein means are provided for flexing a wall of one of said guides to provide pressure engagement between said guide and said member.

3. In a device of the class described, the combination with an annular casing open at one end, adapted to be supported on a machine, of a mounting removably fitting the inner wall of said casing and comprising a movable member for supporting the shank of a tool, a set of guides engaging the opposite sides of said member to slidably support it therebetween, means for securing said guides together, said member being formed with a through screw threaded opening, a feed screw supported in said opening, means on one of said guides abutting the opposite ends of said screw to prevent axial movement thereof, the exterior walls of said guides being shaped to slidably fit the inner walls of said casing, whereby the mounting may be bodily positioned in or removed therefrom, and means for securing the mounting in the casing.

4. In a tool mounting, the combination with a casing adapted to be mounted on a machine, of a movable member formed with a seat to receive the shank of a tool, a guide member seated on the inner wall of said casing and comprising a base forming a slide way for one side of said member, spaced guides engaging the opposite side of said member, means for securing said spaced guides and base in fixed relation, said member being formed with a through screw threaded opening, a feed screw supported in said opening, upstanding walls at the opposite sides of said base abutting the opposite ends of said screw to prevent axial movement thereof and limit the movement of said member in either direction, and means for securing one of said guides in said casing.

5. In a tool mounting, the combination with a casing adapted to be mounted on a machine, of a movable member formed with a seat to receive the shank of a tool, a guide device comprising a base fitting the inner wall of said casing and having spaced upstanding walls, the surface of the base between said walls forming a slide way for one side of said member, spaced guides engaging the opposite side of said member and secured to the upper ends of said walls, said member being formed with a through screw threaded opening, a feed screw supported in said opening and engaging said walls at its opposite ends, whereby said walls prevent endwise movement of said screw and limit the endwise movement of said member, and means for securing said first mentioned guide to the wall of said casing.

6. A mounting as claimed in claim 5 wherein said base is formed with an elongated through opening below said slide way and substantially co-extensive therewith, and means arranged to engage the wall of said base between said slide way and opening for flexing said wall against said movable member.

7. A mounting as claimed in claim 5 wherein said base is formed with an elongated through opening below said guide way and substantially co-extensive therewith and a screw threaded opening disposed at right angles to said first mentioned opening and extending outwardly therefrom, and a screw fitting said threaded opening and arranged to be tightened against that por-

tion of the base forming said guide way to flex it against said movable member.

8. In a tool mounting, the combination with a casing adapted to be supported on a machine, of a movable member formed with a seat to receive the shank of a tool, a base in said casing comprising spaced upper and lower walls rigidly connected along their opposite sides to form a through opening between them and upstanding walls at the opposite ends of said upper wall extending at right angles to the connections between said upper and lower walls, the upper surface of said upper wall between said upstanding walls forming a slide way for one side of said movable member, a guide device in said casing supported at its opposite ends on said upstanding walls and engaging the opposite side of said movable member, said movable member being formed with a through screw threaded opening, a feed screw mounted in said screw threaded opening and abutting said upstanding walls at its opposite ends, whereby said walls prevent endwise movement of said feed screw, the lower wall of said base being formed with a screw threaded opening, a screw in said last mentioned opening arranged to be tightened against said upper wall of said base to flex it, whereby the slide way engages said movable member under pressure, and means for securing said base to the wall of said casing.

9. A mounting as claimed in claim 1 wherein means are provided for flexing a wall of one of said guides for providing pressure engagement thereof with said member and separate means are provided for flexing one of the remaining guides for locking said member against movement.

10. A mounting as claimed in claim 5 wherein one of said spaced guides is formed with an elongated opening and a threaded opening leading therefrom, and a screw in said threaded opening arranged to engage the remote wall of said elongated opening to flex the walls of said guide toward said member.

11. In a tool mounting, the combination with a casing adapted to be mounted on a machine, of a movable member formed with a seat to receive the shank of a tool, a guide device comprising a base fitting the inner wall of said casing and spaced upstanding walls, the surface of the base between said walls forming a slide way for one side of said member, said base below said slide way being formed with an elongated opening and below said opening formed with a screw threaded opening, a screw in said threaded opening arranged to be tightened against the remote wall of said elongated opening to flex said slide way against said member, spaced guides engaging the opposite side of said member and supported on the upper ends of said walls, one of said spaced guides above its guide surfaces being formed with an elongated opening and above said opening formed with a screw threaded opening, a screw in said last mentioned threaded opening arranged to be tightened against the remote wall of said last mentioned elongated opening to flex the guide surfaces of said spaced guide against said member, said member being formed with a through screw threaded opening, a feed screw mounted in said opening and engaging said walls at its opposite ends, whereby said walls prevent endwise movement of said screw, and means for securing said first mentioned guide to the wall of said casing.
